CLAIM

The ornamental design for a combined reversible child
resistant closure and screw cap for containers, as shown
and described.

DESCRIPTION

FIG. 1 is a top perspective view of a combined reversible
child resistant closure and screw cap for containers,
showing my new design;

FIG. 2 is a bottom perspective view thereof;

FIG. 3 is a side elevational view thereof;

FIG. 4 is a top plan view thereof; and

FIG. 5 is a bottom plan view thereof.

FIG. 1

FIG. 2

FIG. 3

FIG. 4

FIG. 5
